UNITED STATES PATENT OFFICE.

WILLIAM J. YEOELL, OF NEW YORK, N. Y.

PRINTING-SURFACE AND METHOD OF MAKING SAME.

SPECIFICATION forming part of Letters Patent No. 782,184, dated February 7, 1905.

Application filed August 29, 1904. Serial No. 222,646.

To all whom it may concern:

Be it known that I, WILLIAM J. YEOELL, of New York, N. Y., have invented certain Improvements in Printing-Surfaces and Methods 5 of Making Same, of which the following description, in connection with the accompanying drawings, is a specification, like numerals on the drawings designating like parts.

This invention relates to printing-surfaces, 10 and has for its object the production of a printing-surface free from pits, crevices, and acute angles throughout its area and presenting smooth uniformly plane printing portions with clearly-defined boundaries, these 15 improvements over existing surfaces being of special advantage when embodied in a pliable sheet-metal printing-surface of the sort forming the subject-matter of my application for United States Letters Patent, Serial No. 20 208,632, filed May 18, 1904, although I contemplate the embodiment of various of the 25 improvements in printing-surfaces made up of movable type and in any other field to which my improvements may be applicable by reason of their nature.

In a printing-surface or "form" of common printer's type assembled with square-headed "spaces" between the words and lines of type the crevices in the type-faces and in 30 the angles between adjacent type, words, and lines afford lodging-places for ink and foreign substances, and the acute angles tend to tear stereotype and other matrices when applied thereto. In stereotyping great annoyance occurs from defects in casting, owing 35 to the extent of surface cast and the impossibility of removing easily and replacing defective portions. Half-tones and other etched surfaces have characteristic and very prejudicial surface roughnesses, owing to the uneven action of the acid or etching medium upon the varying grain of the metal, often undercutting the "dots" of the half-tone plate and the relief printing-surface of other 40 plates, thereby impairing the printing and reproductive qualities of such surfaces. To alleviate these difficulties of operation incidental to the tendency to engage crevices, pits, 45 roughnesses, and the like, elaborately-lami-

nated matrix materials have been devised with 50 close-grained faces, stiff backing layers, and soft intervening packing layers, and extra layers for other functions, this complex matrix being applied moist and baked in place upon the type or other surface to be reproduced, 55 according to the most approved practice at the present day, and even then it frequently happens that the matrix is engaged by the defects above enumerated. Electrotype present less 60 roughnesses usually, but are not entirely free from unevenness, and have the acute angularities and square interstices characteristic of the type and many of the roughnesses of the half-tones they reproduce, while the expense of 65 their production and the time consumed are excessive. The absence of a satisfactory printing-surface requiring less time and skill in its production than the electrotype has led in the case of half-tones to the use of etched half-tone male and female steel dies, between which 70 a metal plate is stamped, with considerable initial outlay of time in preparing the dies, disadvantageous shock in the stamping operation, and a result which while favorable in point of quantity of product is not uniform 75 and does not improve in quality upon the dies, which possess of necessity the characteristic etching roughnesses already set forth.

Briefly stated, my improvement in the art of producing printable replicas direct from 80 the original type, electrotype, half-tone, and engraved, or other relief or intaglio forms eliminates the necessity for an engraved, etched, cast, or otherwise prepared metal 85 cooperating die and is preferably carried into effect by rolling a sheet of metal or suitable material between said type or other form and a blanket of pulpy material.

A sheet of metal can be treated in accordance with my invention to present on its relief side a smooth, uniformly plane surface 90 replication of the type or other printing-surface on which it was formed and superior to said original in printing qualities. Moreover, intermediate the relief printing characters, 95 whether they be dots, lines, or extended surfaces, the sheet-metal replica will have deep rounded interstitial concavities, so that a stere-

otype or other matrix can actually be made in the usual way from my replica more readily than from the original type-form with its rectangular interspaces and acute angles or the 5 rough half-tone or other etched plate. For the same reason a sheet-metal replica produced by my novel method from the ordinary zinc half-tone plate presents a smoother surface throughout both its printing and non-printing 10 portions, so that it improves in printing qualities over its original, having ideal smooth flat printing portions and intervening spaces which do not retain ink and tend to fill up. Conversely, upon its intaglio side such a replica 15 presents smooth intaglio portions corresponding to the printing portions of the original and rounded interstitial convexities, so that the replica constitutes in itself an ideal matrix into which can be formed by rolling, 20 pressing, casting, brushing, or otherwise stereotype or other metal or material suitable to form a secondary replica, such as a stereotype-plate or another thin replica sheet. If the replica be placed in a curved stereotype- 25 casting box and stereotype metal cast into it, a stereotype-plate with a perfect smooth printing-surface results, and after use the curved plate may be placed in the melting-pot, the stereotype metal melted, and the zinc 30 or other replica floated off uninjured and may be filed away for future reference or sent by mail or otherwise for use elsewhere, this being one of the exceeding important capabilities of my invention. Analogous thereto is 35 the treatment of the replica, as already suggested, by brushing into its intaglio side sufficient hot metal to fill up the depressions and aid in rendering the plate rigid without increasing its weight unduly or rendering it in- 40 flexible, the plate thus formed being mailable at low expense. If the replica be of zinc it may have molten zinc brushed or otherwise applied to it, and other metals may be reinforced in kind to form an integral plate of 45 homogeneous material. Otherwise copper, &c., may be electrodeposited quickly into the recesses of copper or the like, and aluminium may be cast into aluminium or other metal. As the intaglio side fits snugly upon the type 50 original, advantage may be taken of this to press tin-foil or other soldering or similar medium into, say, a brass or copper replica, so that when the common fusible metal used to back electrotypes is poured in it will form 55 speedily perfect and complete union with the replica throughout its area and leave no air-holes or other imperfections. A replica thus backed may be trimmed and mounted just like an electrotype, but needs no truing-up, 60 dressing, overlay, or other manipulation ordinarily.

As the metal sheet has the smooth continuous surface above described, I have found it possible to dispense with complex matrices

and substitute in my blanket a homogeneous 65 material analogous to a pulpy paper, presenting a relatively soft face to receive the impression of the type or other original, and having preferably an integral harder stratum to limit the degree of entrance of the type and 70 insure the formation of a homogeneous, smooth, flat, and clearly-defined printing portion upon the replica. This makes an admirable matrix material for general use, and I claim it as such. I find it convenient at times to 75 introduce into the material of the blanket a medium tending to enable a sharper impression of the original to be secured therein, and gutta-percha, rubber, lac, gypsum, or the like may be used, according to the definition required by 80 the subject, a solution of one of the above materials serving when applied upon one side of the blanket not only to permeate the latter, but also to form by deposition the stratum already mentioned. The blanket material may 85 be freshened up after use and utilized a plurality of times, if desired.

The various features of my invention will be illustrated fully in the accompanying drawings and may be understood thoroughly from 90 the specification read in connection with the foregoing general description, together with the claims.

In the drawings, Figure 1 illustrates in vertical section apparatus adapted to produce 95 printing-surfaces in accordance with my invention. Fig. 2 shows in section a replica embodying my improvements. Figs. 3 and 4 are similar views of a form of type and portion of a half-tone plate from which a replica such as that illustrated in Fig. 2 can be produced. Fig. 4^a shows in section a replica embodying my improvements formed from the half-tone plate shown in Fig. 4. Fig. 5 shows the replica of Fig. 2 backed, trimmed, 100 and mounted. Fig. 6 shows the replica of Fig. 2 with its intaglio portions on the reverse side filled. Fig. 7 shows in section a curved stereotype-plate provided with a replica-surface embodying my improvements. Fig. 8 shows in section a replica provided with a soldering medium. Fig. 9 is a similar view of two replicas produced at one operation, and Fig. 10 shows in section a blanket of my improved 105 construction.

In the embodiment of my invention selected for illustration and description as a convenient form to enable a ready and complete understanding of my improvements the reference-numerals 1 and 2 designate a couple of rolls 110 indicated diagrammatically and which may be suitably mounted and driven, 3 designating a bed traveling between the rolls and arranged to receive the type or other form or original 4, from which it is desired to produce the print- 115 able replicas, a chase 5 of well-known character being illustrated to hold the type.

The numeral 7 designates a sheet of thin

copper, brass, zinc, steel, aluminium, or other suitable material which is to receive the impression of the form, and 6 designates the blanket superimposed upon the sheet 7.

5 Upon starting the rolls the bed 3, with the form 4, sheet 7, and blanket 6, will be drawn through the couple, which will be set, preferably, to exert a relatively light pressure to be determined by the character of the work. 10 The form, sheet, and blanket may, if necessary, and preferably will, be drawn through again, the rolls being set up toward each other into approximately the position shown with respect to the rolls 8 and 9, which latter may 15 be considered a second set to act on the form, sheet, and blanket for the second impression without the necessity for reciprocation of the bed 3. Additional couples of rolls may be added to give a narrower bight. If desired, the 20 blanket 6 may be placed directly upon the form 4 and run through the rolls to receive a preliminary impression before they are run through with the sheet 7. After the replica 7 has been stripped from the form 4 it will be 25 in the shape shown in Fig. 2, and it may be backed, trimmed, mounted, and otherwise manipulated just as an electrotype-shell is treated, but with greater ease, as the sheet metal is more homogeneous and is less porous than 30 electrodeposited metal. Inasmuch as inaccuracies in the level or make-up of the type or other form can be corrected by overlays or "make-ready" during the rolling or pressing of the sheet metal in a manner well-known 35 to all skilled in the printing art and not requiring description herein, I find that the metal replica can usually be backed, trimmed, and mounted at once and with but little need for manipulation and gives a perfect printing- 40 block, as illustrated in Fig. 5, where the replica 7 has the usual backing 10 of soft metal and is tacked at 11 to the wooden block 12.

Fig. 3 is a view in vertical section, on an enlarged scale, of the type original, (shown in Fig. 41,) and the square interspace between each type and the crevices 13 necessarily existing between the individual type 14 and intervening spacing devices 15 appear clearly, so that the contrast is well shown with my sheet- 50 metal replica 7 in the neighboring Fig. 2, where the square interspaces and crevices of the type disappear and are replaced by the rounded interstitial concavities 16, merging without acute angles into the smooth and, in 55 fact, highly-polished printing portions 17, the faces whereof are uniformly flat and their boundaries clearly defined, so that they present an ideal printing-surface, as it will retain ink on its printing portions and not elsewhere.

60 In Fig. 4 I show a half-tone plate 18, the etched surface whereof exhibits the characteristic roughness of etched surfaces, and in Fig. 4^a I have shown a metal replica 57 from the half-tone surface 19 produced by my process.

In this replica the roughnesses disappear, and 65 the replica 57 shows the qualities of smoothness, &c., already described in greater degree as an improvement over the original half-tone than the replica 7 shows improvement over its type original. 70

In Fig. 6 I illustrate a replica 27, into the intaglio portions 20 of which has been brushed a filling 21 of molten zinc in a pasty state or at a temperature too low to injure the replica, the replica 27 in this instance being of zinc, 75 so that a strong homogeneous one-metal plate is available, thin, light, and malleable at low cost.

Fig. 7 shows a zinc replica 37, which has been placed in a casting-box and provided with a backing 22 of stereotype metal, so that 80 the curved stereotype-plate thus produced has an ideal printing-surface separable from the backing, which may be melted off without injury to the surface and the latter filed away or other disposition made thereof. 85

In backing the replicas a foil or soldering medium may be used to advantage, as shown in Fig. 8, where 47 designates the replica, in this instance of brass, and 23 a layer of tin-foil pressed upon the same original type as 90 the replica 47, into which therefore it fits exactly, so that when molten backing metal is introduced against the foil the latter fuses at once and a perfect complete union of the backing with the replica is effected throughout the 95 area thereof. Either the replica or the uniting medium, or both, may be coated with a suitable flux 24, such as muriatic acid, if desired, before being united.

In Fig. 9 I have illustrated two metal replicas produced at the same time by feeding two superimposed sheets of metal 67 77 through the rolls between the type and blanket. 100

One embodiment of my improved blanket is shown in Fig. 10, where the reference-number 28 designates the homogeneous pulpy or felted paper or analogous material of which the blanket is composed and which presents a relatively soft face 29 to receive the impression 30, while 31 designates the harder 105 stratum acting to limit the degree of entrance of the type into the face and to cause the production of highly-compacted smooth inner faces 32 in the impressions, so that the replica will derive therefrom perfectly smooth flat 110 printing portions. The lighter portion of the blanket at the left of Fig. 10 indicates a portion which has not been treated, while at the right of Fig. 10 the darkened portion indicates the sharpening medium--such as gutta-percha, 115 rubber, lac, or the like--the presence of which insures resistance of the face 29, its entrance into the intaglio portions of the type, and consequent definition in the replica. In this 120 instance the harder stratum 31 is formed by 125 deposition of the sharpening medium in a solution passed through the material 28 from the back.

A fresh blanket may be used for each replica, or a blanket once impressed may be used many times, both in connection with my improved process and for general matrix purposes.

Having described my invention thus fully and convenient means by which to carry my improvements into effect, it is to be understood that I do not limit myself to the specific 10 apparatus, material, or sequence of operations selected for illustration and description nor in general otherwise than as set forth in my claims read in connection with this specification.

15 What I claim, and desire to secure by Letters Patent, is—

1. As an article of manufacture, a replica swaged over printable type or the like, presenting on its relief surface a printable replication of the type or other relief surface over which said replica was swaged, said replica printing-surface having rounded interstitial concavities in the non-printing portions of individual letters and words, and between lines or 25 other printing characters, and said printing characters having uniformly plane smooth printing-surfaces with clearly-defined boundaries, substantially as described.

2. As an article of manufacture, a thin metallic replica-plate swaged up over printable type or the like and presenting on its relief surface a printable replication of the type or other relief surface over which said replica was swaged, said replica printing-surface having rounded interstitial concavities in the non-printing portions of individual letters and words, and between lines or other printing characters, and said printing characters having uniformly plane smooth printing-surfaces with clearly-defined boundaries, said replica-plate being provided with a metallic backing, 40 substantially as described.

3. That improvement in the art of producing printable replicas direct from type and engraved, or other relief or intaglio forms, without an engraved, etched, cast or otherwise-prepared metal co-operating die, said improvement consisting in rolling a sheet of suitable material between said type or other form and 45 a blanket, to swage in said material relief printing characters, with rounded interstitial concavities in all the non-printing portions of individual characters and of the extended intervening spaces, substantially as described.

55 4. That improvement in the art of producing printable replicas direct from type or the like, said improvement consisting in rolling a sheet of suitable material between said type or the like and a blanket of a pulpy character, to 60 swage in said sheet material a printable replication of said type, with rounded concavities in the non-printing portions of individual letters and words, and between lines, substantially as described.

65 5. That improvement in the art of producing

printable replicas direct from type or the like, said improvement consisting in rolling a sheet of metal between said type or the like and a blanket of a pulpy character, to swage in said sheet metal a relief printable replication presenting characters having uniformly flat, smooth printing-surfaces with clearly-defined boundaries, substantially as described. 70

6. That improvement in the art of producing printable replicas direct from type or the like, 75 said improvement consisting in pressing a sheet of suitable material into the interstices and over the relief portions of said type or the like through the medium of a blanket of a pulpy character between which and said type, 80 or the like, said sheet is embraced and caused to assume a printing-surface presenting a series of relief printing characters having uniformly flat, smooth printing-surfaces with clearly-defined boundaries and rounded interstitial concavities, substantially as described. 85

7. That improvement in the art of producing printable replicas consisting in pressing a sheet of metal between type or the like and a blanket of pulpy material containing a sharpening medium, substantially as described. 90

8. That improvement in the art of producing printable replicas consisting in pressing a sheet of metal between type or the like and a pulpy paper containing a solution of lac, or similar sharpening medium, substantially as described. 95

9. That improvement in the art of producing printable replicas, consisting in pressing type or the like into a blanket of material of the character of paper-pulp, and pressing between said type and the blanket thus impressed a sheet of metal to receive the impression of said type and present a relief printable replication thereof in printing characters having uniformly flat, smooth printing-surfaces with clearly-defined boundaries, substantially as described. 100

10. That improvement in the art of producing printable replicas, consisting in pressing a sheet of suitable material between type or the like and a blanket of suitable material, removing said sheet, and thereafter pressing between said type and said blanket thus impressed another sheet of material suitable to form a printable replica, substantially as described. 110

11. That improvement in the art of producing printable replicas consisting in pressing between type or the like and a blanket of pulpy paper or other suitable material, a plurality of sheets of material suitable to form printable replicas, thereby producing separable replicas presenting respectively relief printing characters and rounded interstitial concavities, substantially as described. 120

12. That improvement in the art of producing printable replicas consisting in pressing a sheet of metal between type or the like and a blanket presenting a relatively soft surface 130

toward the type and having a harder stratum to press said metal firmly against the face of said type, thereby to force the metal deep into the intaglio portion of said type, insuring definition in the replica and also insuring a smooth, uniformly plane printable surface replication of the printing-surface of said type.

Signed at New York, in the county of New York and State of New York, this 27th day of August, A. D. 1904.
